DESIGN.

G. HARTJE.

RING.

No. 16,916.

Patented Sept. 28, 1886.

UNITED STATES PATENT OFFICE.

GEORGE HARTJE, OF NEW YORK, N. Y.

DESIGN FOR A RING.

SPECIFICATION forming part of Design No. 16,915, dated September 28, 1886.

Application filed June 10, 1886. Serial No. 201,807. Term of patent 14 years.

To all whom it may concern:

Be it known that I, GEORGE HARTJE, a citizen of the United States, residing at New York, in the county and State of New York, ⁵ have invented and produced a new and original Design for Rings, of which the following is a specification.

My invention consists of a new and original design for rings, consisting of interlacing ¹⁰ strands or raised portions on the ring to represent wicker-work, the same being generally termed "basket-work."

The distinguishing features of my design are pointed out in the following description and ¹⁵ claims, and shown in the drawing forming part of this application, in which the figure is a perspective view showing the design.

In said drawings the reference-letter A designates a ring having a jewel or stone, c, in any ²⁰ usual setting, c. Upon the face of said ring are raised interlaced portions or strands a and b, which pass or appear to pass alternately above and beneath each other, and thereby present the appearance of wicker or basket ²⁵ work. The face of the ring may be convex or flat, and the interlacing portions a and b may be either flat or rounded in form. The setting

³⁰ c may be raised or low, and the stone may be selected as desired. The exact shape and relative proportions of the band are not essential features of the design, and may be varied without affecting or altering the latter, the design consisting of a set-ring having upon its face a representation of basket-work.

What I claim as new, and desire to secure ³⁵ by Letters Patent, is—

1. The design for a set-ring herein shown and described, the same consisting of a representation of basket-work upon the external or exposed face of the ring and around the setting.

2. The design for a ring herein shown and described, the same consisting of a setting, c, and a representation of basket-work, a b, upon the external face of the ring and around the setting.

In testimony whereof I have hereunto set my hand and seal in the presence of two subscribing witnesses.

GEORGE HARTJE. [L. s.]
